UNITED STATES PATENT OFFICE.

HERTHA AYRTON, OF LONDON, ENGLAND.

LANTERN OR INCLOSURE FOR LAMPS.

1,125,438.

Specification of Letters Patent.

Patented Jan. 19, 1915.

Application filed February 3, 1914. Serial No. 816,139.

To all whom it may concern:

Be it known that I, HERTHA AYRTON, residing at 41 Norfolk Square, Hyde Park, in the county of London, England, scientist, have invented new and useful Improvements in or relating to Lanterns or Inclosures for Lamps Used for Projecting a Beam of Light, of which the following is a specification.

10 This invention relates to lanterns or inclosures for lamps used for projecting a beam of light.

The invention has for its object to provide means for keeping the lamp or lantern or 15 inclosure cool and well ventilated.

In common with other apparatus of this kind, a lantern or inclosure made in accordance with the present invention comprises an inner shield, body part, or lantern 20 forming a chamber within which is arranged the lamp, and an outer shield having a vertical ventilating space between it and the inner shield.

According to the present invention an inclosure or lantern for lamps used for projecting a beam of light comprises an inner shield, body part, or lantern inclosing the lamp and an outer shield surrounding the inner shield and spaced apart therefrom 30 so as to form a vertical ventilating space between the two shields which ventilating space is open to the atmosphere at its upper and lower ends. If required the inner shield may be of wire gauze, perforated 35 metal, or equivalent material, and the outer shield may be of asbestos or other suitable heat insulating material suitably strengthened in some cases by wire gauze or equivalent reinforcing material. In some cases the 40 outer shield may be of metal which may or may not be lined or covered with asbestos or the like. Where the invention is applied to gas or other lamp with a naked flame having no chimney the foraminous nature 45 of the inner shield may serve to supply air to the flame. The ventilating space or spaces are preferably arranged so that the ventilation is symmetrical or substantially so.

50 According to this invention as applied to arc lamps the inner inclosure of what is hereinafter called the "lamphouse" is made entirely, or for the most part, of wire gauze or perforated metal, or any other suitable 55 material, and the outer cover of asbestos, the cover being either of asbestos cloth hang-

ing loose or stretched on a frame at some little distance from the wire gauze or of sheet asbestos similarly placed. In a modification the outer shield may be of sheet metal or any other convenient suitable material.

The accompanying drawings show one construction of lamphouse made in accordance with this invention as applied to an arc lamp.

Figure 1 is a front elevation, the left side being a section on line A B of Fig. 3. Fig. 2 is a side elevation, the upper half being a section on line C D of Fig. 3. Fig. 3 is 70 a plan, the lower half being a section on line E F of Fig. 2. Figs. 4 and 5 are perspective views showing details of the structure. Figs. 6 and 7 are further details.

The lamphouse shown in the drawings 75 consists of an inner chamber *a* of wire gauze, the four vertical sides of the chamber are inclosed by an outer frame or wall *b* suitably spaced apart from the inner chamber so as to leave a ventilating space *c*, open at 80 top and bottom. The air space is shown tapered from the bottom to the top but this is not essential.

In the front of the lamphouse the cylindrical extension *d* stretches across the air 85 space and is adapted in any suitable way to carry the lens which is not shown. The top of the inner chamber *a* is covered in by a plate *a'* and a chimney *a²* is fitted toward the rear end.

The framework of the structure may be 90 made in any suitable way for example the skeleton framework may be made as shown in the perspective views Figs. 4 and 5, the inner gauze walls and the outer asbestos 95 walls being clamped in position by suitable frames *a³* and *b³* respectively screwed in position as indicated in Figs. 1 to 3.

Fig. 6 shows an enlargement of the construction of the tube for receiving the lens. 100 *f f'*, Fig. 2, are the slots in the side walls of chambers which permit the operating handle to pass out and leave room for the operation thereof. Fig. 7 shows how the said slots are fitted with a cone or sleeve *g* 105 of asbestos cloth which is fitted at its larger end *g'* into the wire gauze of the inner chamber, the small end *g²* being wired around the handle *h* or otherwise secured thereto. Such cones are also fitted on to the 110 corresponding slots in the outer shield.

In the construction shown a door is pro-

vided in the front half of the lamphouse at *i* Figs. 2 and 3. The outer part of the door which is of asbestos and coincides with the outer inclosure is hinged as at *i*² (see Fig. 5) and the inner part of the door *i*³ which is of gauze and coincides with the inner gauze chamber is connected to and carried upon the outer part *i*' by means of spacing bars *j* Fig. 3.

- 10 It will readily be seen from the drawings that free ventilation is provided around the whole of the inner chamber by the air space *e* the cooling being facilitated by the wire inner gauze inclosure, the whole structure 15 providing an ample and very symmetrical and well distributed ventilation. The outer insulating wall of asbestos protects the operator from excessive heat. If required the ventilation air space need not extend 20 around the whole of the lamphouse for example the front ventilating air space may be dispensed with.

Having described one construction of my 25 invention particularly in regard to arc lamps it would be readily understood how it may be applied in an equivalent manner to lamps of other kinds used for projecting a beam of light, as hereinbefore mentioned.

What I claim and desire to secure by Letters Patent is:—

- 30 1. An inclosure for lamps used for projecting a beam of light comprising an inner shield disposed around the lamp, and an outer shield disposed around the inner shield and spaced apart therefrom, the space between the inner and outer shields being open to the atmosphere at its upper and lower ends, the inner shield being made, for the most part, of foraminous material, 35 as set forth.

- 40 2. An inclosure for lamps used for pro-

jecting a beam of light, comprising an inner shield disposed around the lamp, and an outer shield disposed around the inner shield and spaced apart therefrom, the space between the inner and outer shields being open to the atmosphere at its upper and lower ends, the inner shield being made, for the most part, of foraminous material and the outer shield being made, for the most part, of heat insulating material such as asbestos, as set forth.

3. An inclosure for lamps used for projecting a beam of light comprising an inner shield disposed around the lamp, and an outer shield disposed around the inner shield leaving a symmetrical space around the lamp between the inner and outer shields, which space is open to the atmosphere at the upper and lower ends the inner shield being made, for the most part, of foraminous material, as set forth.

4. An inclosure for lamps used for projecting a beam of light comprising an inner shield disposed around the lamp, and an outer shield disposed around the inner shield leaving a symmetrical space around the lamp between the inner and outer shields, which space is open to the atmosphere at the upper and lower ends the inner shield being made, for the most part, of foraminous material and the outer shield being made for the most part, of heat insulating material such as asbestos, as set forth.

In witness whereof, I have hereunto signed my name in the presence of two subscribing witnesses.

HERTHA AYRTON.
